UNITED STATES PATENT OFFICE

2,482,186

RUG STRETCHER

Glenn L. Huff, San Diego, Calif.

Application July 5, 1947, Serial No. 759,028

1 Claim. (Cl. 45—24)

1

My invention relates to a rug stretcher more particularly for use in connection with cleaning and sizing operations performed on rugs and the like, and the objects of my invention are:

First, to provide a rug stretcher of this class which employs very simple means for attaching the rug thereto whereby considerable time is saved in connecting the rug to the stretcher.

Second, to provide a rug stretcher of this class which stretches a rug evenly throughout its entire length.

Third, to provide a rug stretcher of this class which maintains the same in flat contiguous relationship with a flat surfaced object.

Fourth, to provide a rug stretcher of this class which automatically holds the rug in stretched position for any length of time desired.

Fifth, to provide a rug stretcher of this class having novel fairlead and bracket support means for controlling the retracting cables thereof whereby said fairleads may be positioned on the edge of a board or on the upper surface thereof as desired.

Sixth, to provide a rug stretcher of this class which insures the maintenance of a rug shape and size when said rug is cleaned, and

Seventh, to provide a rug stretcher of this class which is very simple and economical of construction, efficient in operation, and which will not readily deteriorate or get out of order.

With these and other objects in view, as will appear hereinafter, my invention consists of certain novel features of construction, combination and arrangement of parts and portions as will be hereinafter described in detail and particularly set forth in the appended claim, reference being had to the accompanying drawing and to the characters of reference thereon forming a part of this application in which: Figure 1 is a top or plan view of my rug stretcher, Figure 2 is an enlarged sectional view thereof taken from the line 2—2 of Figure 1, and Figure 3 is an enlarged sectional view taken from the line 3—3 of Figure 1.

Similar characters of reference refer to similar parts and portions throughout the several views of the drawing.

The board 1, strap 2, bar 3, cables 4 and 5, fairleads 6 and 7, brackets 8 and 9, drum 10, ratchet wheel 11, ratchet pawl 12, crank 13, and drum frame 14 constitute the principal parts and portions of my rug stretcher.

The board 1 is a substantially flat, smooth-surfaced board upon which my rug stretcher is installed. This board may be in the form of a platform, floor, wall or other similar surface as

2

desired. For example, my rug stretcher may be installed in connection with a vertical wall, the floor of a room or the like but is preferably installed in connection with a moveable board, or open frame platform, for convenience of handling. The strap 2 and the bar 3 are each provided with upwardly projecting spike portions arranged to extend through the border of a rug for engaging same. The strap 2 is provided with upwardly extending spike portions 2a similar to the spike portions 3a of the bar 3 as shown in Figure 3 of the drawing. It will be noted that the strap 2 is secured to the board 1 by means of screws 2b and that the bar 3 is movable over the surface of the board 1 and connected to the cables 4 and 5 by means of the connection clips 3b and 3c respectively. These cables 5 pass through fairleads 6 and 7 which are conventional self aligning fairleads and these fairleads 6 and 7 are secured to the brackets 8 and 9 respectively which are fixed on the board 1 as shown best in Figs. 1 and 3 of the drawing. These brackets 8 and 9 are substantially identical in form except that they are opposite hand arranged to be fitted to opposite ends of the board 1 in opposed relationship to each other. The bracket 9 as shown in Figure 3 of the drawing is provided with intersecting angular surfaces 9a and 9b arranged to support the bracket 1a of the fairlead 7 in different positions substantially 90 degrees apart whereby the bracket 9 may be connected to either the side or the edge of a board for properly holding the fairlead 7 in certain parallel relationship with the surface of the board 1. The varying position at the edge of the board is illustrated in Figure 3 of the drawing by dash lines. The drum frame 14 is secured to the upper surface of the board as shown in Figure 2 of the drawing or may be secured to the edge thereof in alignment with the bracket as shown by dash lines in Figure 3 of the drawing. This drum frame 14 supports the drum 10 in connection with the board which is provided with separate winding spools 10a and 10b arranged to receive the cables 4 and 5 separately. The ratchet wheel 11 is fixed in connection with the drum at the outer side of the drum frame 14 and the ratchet pawl 12 is pivoted to the drum frame 14 by means of the pin 12a and engages the teeth 11a of the ratchet wheel 11 preventing said ratchet wheel 11 from rotating in a counter clockwise direction. Fixed to the drum 10 is the crank 13 arranged to rotate the drum 10 within the drum frame 14 for winding the cables 4 and 5 on the spool portions 10a and 10b whereby

opposite ends of the bar 3 may be evenly retracted from the strap 2.

The operation of my rug stretcher is substantially as follows: When it is desired to stretch a rug, clean a rug or to size the same, one edge of the rug is connected to the spikes 2a of the strap 2. The opposite edge of the rug is connected to the spike portions 3a of the bar 3. When the crank 13 is rotated in a clockwise direction rotatedly operating the drum 10 and winding the cables 4 and 5 thereon in separate relationship from each other on the spool portions 10a and 10b of said drum 10. This causes the cables 4 and 5 to pass through the fairleads 6 and 7 respectively which direct the cables 4 and 5 in substantially a direction at right angles from which they pull the bar 3. The ratchet pawl 12 engages the teeth 11a of the ratchet wheel 11 maintaining the same from rotation in the counter clockwise direction thus the drum 10 is held in certain position when the cables 4 and 5 are wound tight stretching the rug between the strap 2 and bar 3. When a rug is cleaned it is permitted to dry in connection with the rug stretcher in its stretched relation between the strap 2 and bar 3 or a rug may be stretched beyond its normal size and permitted to retract to its normal size after it has shrunk. The brackets 8 and 9 may be positioned on the edge of the board 1 if desired as shown by dash lines in Figure 3 of the drawing and the drum frame 14 may be likewise positioned on the edge of the board 1 to align with the fairleads 6 and 7 held in connection with the brackets 8 and 9. It will be noted that during the shifting of the brackets 8 and 9 from the side of the board to the edge of the board the fairleads are changed from one of the angular portions 9b to the angular portion 9a as shown in Figure 3 of the drawing whereby the fairlead 7 is maintained in substantially parallel relationship with the side of the board and the same condition is true of the fairlead 6 in connection with the bracket 8.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claim.

Having thus described my invention, what I claim as new and desire to secure by Letters Patent is:

In a rug stretcher of the class described, the combination of a stationary strap having a plurality of extending spikes, a movable bar laterally adjustable relatively to said strap having a plurality of extending spikes, said spikes on said strap and said bar arranged to penetrate the edge of a rug, cables in connection with said bar and means for retracting said cables laterally thereof, 15 fairlead means having base portions and supporting said cables in spaced relationship to said bar, said retracting means including a drum and crank, ratchet means in connection with said drum and crank for holding said cable and said 20 bar in certain position after retraction relatively to said strap, and brackets having two separate fairleads supporting bases angularly disposed to each other and intersecting and supporting said fairlead means on said angular base portions.
